UNITED STATES PATENT OFFICE.

JAMES BAKER, OF ST. LOUIS, MISSOURI.

VELOCIPED.

SPECIFICATION forming part of Letters Patent No. 278,007, dated February 27, 1883.

Application filed September 13, 1882. (No model.)

To all whom it may concern:

Be it known that I, JAMES BAKER, of St. Louis, in the State of Missouri, have invented certain new and useful Improvements in Velocipedes; and I do hereby declare that the following is a full, clear, and exact description thereof, reference being had to the accompanying drawings, and to the letters of reference marked thereon, which form part of this specification, in which—

10 Figure 1 is a top or plan view of my velocipede complete. Fig. 2 is an elevation of one side of the velocipede with the two nearest wheels removed to better expose the parts.

15 Fig. 3 is a view in detail showing a section of one end of the axle, its arm and a part of the main frame bearing on a box, through which the axle passes.

20 Similar letters of reference indicate corresponding parts in the three figures.

25 This invention relates to certain novel improvements on four-wheel velocipedes or wagons, which are constructed to be propelled by man-power; and the nature of my invention and improvements consists mainly in a novel construction of the main frame, whereby lightness and great strength are combined, and whereby bearings are afforded for the axles of the front and rear transporting-wheels; also 30 for the front chain-wheel for the driver's seat, and fulera are afforded for the treadles, all of which will be fully understood from the following description when taken in connection with the annexed drawings.

35 The main frame A of the machine is preferably made of gas-pipes for lightness and strength, and it is composed of a rear straight transverse bar, parallel side bars, which latter are contracted in front so that the general 40 horizontal contour of this main frame, which I now letter A, is that of a bottle. The side bars or tubes of this frame are of one piece, bent in the shape shown in Fig. 1, and the rear transverse bar or tube is secured by L- 45 couplings to the rear ends of the side bars.

45 The object of thus constructing the frame A is to give considerable breadth of bearing at and near the rear part for supporting the person who propels the machine, and to afford 50 freedom for turning the two front wheels in guiding the machine around curves. In order

to perfect this frame, I employ two longitudinal flat bars, B B, which possess more or less elasticity. These bars B B are rigidly secured by bolts or other suitable means to the rear 55 transverse bar or tube of the frame A, equidistant from the median longitudinal line thereof. They are parallel to each other and they extend from their points of rigid attachment to the said rear transverse bar of the 60 frame A to points a a. These bars are then bent so as to form stirrups of angular form, and their front ends are rigidly secured to the front curved end of the frame A.

The stirrups I now letter C C, and they are 65 adapted for a purpose hereinafter explained. At the front angles of the stirrups C C they are rigidly secured to a transverse bar, D, the ends of which are bolted fast to the contracted parallel bars or tubes of the main frame A. 70 It will be seen that the longitudinal bars B B serve as springs or a "buck-board" for the seat E, which is suitably mounted on these bars, and made vertically adjustable by any well-known means. This seat is also sustained 75 upon the rear laterally-extended part of the main frame in any suitable manner. The frame and other parts which I have above described I mount on four transporting-wheels.

The two rear wheels, F F, may be made very 80 light and tired with rubber, and the rim or felloes may be secured to hubs spread apart on a sleeve, G, to which they are suitably and rigidly secured. The sleeves of the two wheels F are applied on the arms of the rear axle, H, 85 and are rigidly secured thereto, so as to turn with it, by jamming the sleeves G of the wheels against shoulders b on the axle H, employing nuts, c, for the purpose, and also keys. It will be seen by reference to Fig. 3 that the rear 90 axle is annularly grooved and that the groove on each side receives corresponding ribs formed on a duplex or sectional box, I, which is rigidly bolted to the under side of the rear transverse 95 portions of the main frame A. It will thus be seen that the weight of the person on the seat bears upon the longitudinal bars of the main frame, and that there is a journal-box which may be bushed to sustain the weight of the person and to afford on each side a durable support. The manner of grooving the axle and adapting bearing-boxes therefor prevents 100

endwise play, and also prevents undue vibration while traveling over rough roads. The springy perch also prevents shocks to the man who is sitting upon the seat and propelling the machine.

J designates a transverse tie-bar, which is connected by clips *e e* to the contracted part of the frame A. To this bar a bolster, K, is rigidly secured by clips L, or in any other suitable manner, and by means of an axle-tree, L', the front wheels are applied in a similar manner described for the rear wheels, with this exception, that the front axle is allowed to swivel about a king-bolt, L², and the lower eye of a loop, M, which is rigidly secured to the bolster K.

To the front axle I suitably pivot the bifurcated end of a hand-lever, R, which is of sufficient length to extend back within reach of the person on the seat of the machine, so that he can manipulate the guide-wheels at pleasure.

I will now describe the means which I have invented for propelling the velocipede.

S designates a stirrup which is bolted to the cross-bar and longitudinal bars B B, and which is also bolted in rear of said points to a cross-bar and to said longitudinal bars. At the base of this stirrup I secure the bearing or journal boxes T for the shaft of the front chain-wheel, U, on which shaft are cranks *f f*, arranged in the same plane. In other words, the wristpins of the said cranks are diametrically opposite each other, as shown in Fig. 2.

To the cross-bar *g*, which connects the lower ends of the stirrups of the longitudinal perch-bars B B, are applied or formed studs, on which are fulcrumed the two treadles Q Q, which are pivoted at *h* to links *i i*, that are themselves pivoted to the arms of the cranks *f f*, above referred to. The rear extensions of the treadles Q Q are so located that they are convenient to the feet of the person sitting upon the seat E. The endless chain *x* engages with the teeth on the periphery of the chain-wheel W, and also with

the teeth on the periphery of a chain-wheel, 45 W', keyed on the axle of the rear transporting-wheels. The pivotal connections *h* of the links *i i*, with the treadles, are made in the following manner: I use bolts on which may be applied anti-friction tubes or rollers *j*, which play freely in slots *k*, made longitudinally through or below the said treadles. If the treadles are made of wood, the slots or guides may be made by straps applied to their lower edges. If they are made of metal, the slots or guides may be made directly through them. The object of allowing the lower ends of the links to play freely in slots formed through or below the treadles, and thus to receive independent vibration of these treadles, is to shorten the leverage of the treadles during their descending strokes, and thus afford greater purchase to the feet of the person operating the machine.

Having described my invention, I claim as new—

1. In a velocipede, the combination of the tubular frame A, the two longitudinal bars B B, adapted to brace and tie said frame, the seat E, mounted on said bars, the cross-bar D, rigidly secured to the frame A and to bars B B, and the stirrups C C, forming part of the latter, all constructed and adapted to operate substantially in the manner and for the purposes described.

2. In a velocipede, the combination, with the treadles Q Q, the links *i i*, the chain-wheel and its cranks, of the anti-friction rollers *j*, playing freely in slots *k* of the treadles, formed substantially in the manner and for the purposes described.

In testimony that I claim the foregoing as my own I affix my signature in presence of two witnesses

JAMES BAKER.
